COIN EJECTOR FOR COIN-OPERATED
TIMING MECHANISM

Arnold R. Dahlberg, Raymond T. Larson, and
Richard M. Chapman, Minneapolis, Minn., as-
signors to The Tonex Company, Minneapolis,
Minn., a corporation of Minnesota

Original application September 15, 1950, Serial
No. 185,084. Divided and this application No-
vember 19, 1951, Serial No. 259,390

2 Claims. (Cl. 194—97)

1

Our invention relates to coin ejectors for coin-operated timing mechanisms and is a division of our copending United States patent application S. N. 185,084, filed September 15, 1950, and entitled "Coin-Operated Timing Mechanism."

The primary object of our invention is the provision of a mechanism for positively ejecting a coin from a rotary carrier upon rotation thereof, irrespective of the presence of dust, grease, or sticky substances in the carrier and associated mechanism.

A still further object of our invention is the provision of a device of the class above described which is extremely inexpensive to produce and install and which will render efficient and fool-proof service over a period of years without the need of adjustment.

The above and still further objects of our invention will become apparent from the following detailed specification, appended claims, and attached drawings.

Referring to the drawings, wherein like characters indicate like parts throughout the several views:

Fig. 1 is a view in elevation of a timing device incorporating our invention, as seen from one side thereof;

Fig. 2 is a view in elevation of the opposite side of the device of Fig. 1;

Fig. 3 is a view corresponding to Fig. 2, but showing a pair of coins inserted in the coin chute of our device and a different position of some of the parts;

Fig. 4 is a view corresponding to Fig. 2, but showing a still different position of some of the parts;

Fig. 5 is a view corresponding to Fig. 2, but showing still another position of some of the parts;

Fig. 6 is a transverse section taken substantially on the line 6—6 of Fig. 5; and

Fig. 7 is a wiring diagram illustrating the use of our novel timing mechanism in controlling a power-operated device.

Referring with greater detail to the drawings, the numeral 1 indicates in its entirety a channel-shaped frame having a central main body 2 and parallel side flanges 3. A guide plate 4 is rigidly mounted to the wall 2 by means of screws or the like 5 and is formed to provide a longitudinally-arcuate channel 6 which cooperates with the underlying frame wall portion 2 to provide an arcuate coin chute or passage 7. The plate 4 is further formed to cooperate with the wall 2 to define a recess 8 communicating

with the coin chute 7 and extending laterally outwardly in one direction to one side edge of the guide plate 4, as indicated at 9.

5 A disc-like coin carrier or transfer member 10 is mounted fast on the enlarged end portion 11 of a shaft 12 by suitable means, such as a set screw or the like 13. The carrier 10 is contained within the recess 8, the shaft 12 being journalled in suitable bearings 14 and 15, the former of which is rigidly secured to the frame 1. Rotary movement is imparted to the carrier 10 by an electric motor 8 and suitable reduction gearing, not shown, but contained within a gear housing 17 and coupled to an output gear 18 mounted fast on the shaft 12. The motor 16 and gear casing 17 are rigidly secured to the wall 2 of the frame 1 by machine screws or the like 19, the bearing 15 being mounted fast on the gear housing 17 in axial alignment with the bearing 14.

10 The carrier 9 is provided with a segmental notch 20 which, upon rotary movements of the carrier, is adapted to move into registration with the coin chute 7 to receive a coin therefrom. The bottom or radially-inner portion of the notch 20 forms a cradle or nest 21 in which the coin or token, indicated by the letter x, drops by gravity from the chute 7, and from which the coin drops under the action of gravity when the carrier 10 is rotated to a predetermined extent.

15 Fig. 3 is a view corresponding to Fig. 2, but showing a pair of coins inserted in the coin chute of our device and a different position of some of the parts;

20 Fig. 4 is a view corresponding to Fig. 2, but showing a still different position of some of the parts;

25 Fig. 5 is a view corresponding to Fig. 2, but showing still another position of some of the parts;

30 Fig. 6 is a transverse section taken substantially on the line 6—6 of Fig. 5; and

35 Fig. 7 is a wiring diagram illustrating the use of our novel timing mechanism in controlling a power-operated device.

40 Referring with greater detail to the drawings, the numeral 1 indicates in its entirety a channel-shaped frame having a central main body 2 and parallel side flanges 3. A guide plate 4 is rigidly mounted to the wall 2 by means of screws or the like 5 and is formed to provide a longitudinally-arcuate channel 6 which cooperates with the underlying frame wall portion 2 to provide an arcuate coin chute or passage 7. The plate 4 is further formed to cooperate with the wall 2 to define a recess 8 communicating

45 with the coin chute 7 and extending laterally outwardly in one direction to one side edge of the guide plate 4, as indicated at 9.

50 A disc-like coin carrier or transfer member 10 is mounted fast on the enlarged end portion 11 of a shaft 12 by suitable means, such as a set screw or the like 13. The carrier 10 is contained within the recess 8, the shaft 12 being journalled in suitable bearings 14 and 15, the former of which is rigidly secured to the frame 1. Rotary movement is imparted to the carrier 10 by an electric motor 8 and suitable reduction gearing, not shown, but contained within a gear housing 17 and coupled to an output gear 18 mounted fast on the shaft 12. The motor 16 and gear casing 17 are rigidly secured to the wall 2 of the frame 1 by machine screws or the like 19, the bearing 15 being mounted fast on the gear housing 17 in axial alignment with the bearing 14.

55 The carrier 9 is provided with a segmental notch 20 which, upon rotary movements of the carrier, is adapted to move into registration with the coin chute 7 to receive a coin therefrom. The bottom or radially-inner portion of the notch 20 forms a cradle or nest 21 in which the coin or token, indicated by the letter x, drops by gravity from the chute 7, and from which the coin drops under the action of gravity when the carrier 10 is rotated to a predetermined extent.

60 A normally open switch 22 is contained within a casing 23 and is adapted to be closed by swinging movements of a switch-operating arm 24 in one direction. The casing 23 is secured to the frame 1 by screws or the like 25, the switch arm 24 extending through aligned apertures 26 in the wall 2 and guide plate 4. A pair of aligned slots 27 and 28 in the frame wall 2 and guide plate 4 respectively provide a passageway for swinging movements of the free end 29 of the arm 24, said free end being inturned to project therethrough in parallel relationship to the shaft 12 transversely of the recess 8 and in the path of travel of a coin deposited in the chute 7. A wearing plate 30 is mounted fast on the frame 1 and overlies the slot 27 to limit movement of the free end 29 of the arm 24 in one direction transversely of the path of travel of the coin x. The arm 24 is preferably made from resilient wire or the like and is yieldingly biased toward frictional engagement of the extreme end thereof with the plate 30.

65 The weight of a coin x moving downwardly through the chute 7 is sufficient to cause downward swinging movement of the arm 24 to close the switch 22. The switch 22 is of the type

requiring a relatively short downward swinging movement of the arm 24 to be rendered operative, subsequent movement of the arm 24 being merely an overtravel thereof. With reference to Fig. 7, it will be seen that a coil spring 31 permits overtravel of the arm 24 beyond its switch-closed position closely spaced from the upper limit of its swing to its lower limit of swinging movement shown in Figs. 4 and 5.

A terminal block 32 is mounted on the frame 1 and includes a pair of terminals 33 and 34 which are connected to opposite contact elements of the switch 22 by a pair of leads 35 and 36 respectively. Another pair of terminals 37 and 38 in the block 32 are connected to the motor 16 by a pair of respective leads 39 and 40, see Fig. 7. For the purpose of illustrating utility of our novel timing mechanism, a load in the nature of a motor or the like 41 is shown as having a pair of leads 42 and 43, the former of which is connected to the terminal 37, and the latter of which extends to one side of a power line 44 or like source of electrical energy. The opposite side of the power line 44 is connected to the terminal 34 by a lead 45 and a lead 46 is shown as connecting the lead 43 with the terminal 33. An operating circuit is completed by a jumper wire or the like 47 connecting the terminals 33 and 37.

Operation of the above-described mechanism is initiated by insertion of one or more coins or tokens x into the chute 7. The first inserted coin x descending through the chute 7 makes contact with the end portion 29 of the switch-operating arm 24 and moves the arm 24 downwardly from its switch-open position of Fig. 2 to its switch-closed position of Fig. 3, the weight of a single coin x being sufficient to move the arm and close the switch 22. Closing of the switch 22 completes the circuits through the load 41 and timer 16. Energization of the motor 16 causes the coin carrier 10 to rotate at a predetermined speed in a counterclockwise position with respect to Figs. 2 to 5 inclusive and Fig. 7. As the coin carrier 10 rotates, the switch-operating arm 24 is swung downwardly in a direction out of the path of travel of the coin x until said coin is moved by the carrier out of engagement therewith, after which the free end 29 of the arm 24 is engaged by the peripheral portion of the coin carrier 10 as shown in Figs. 4 and 5 to maintain the switch 22 in a closed position. Normally, when the coin carrier 10 progresses to its position of Fig. 4, the coin x will drop out of the notch 20 under the action of gravity and into a coin-receiver or the like, not shown but commonly used in conventional coin-operated mechanism. Continued rotation of the coin carrier 10 causes the notch 20 therein to be finally moved into full registration with the coin chute 7 as indicated in Figs. 2 and 3. At this point, the leading side 21' of the notch 20 has been moved sufficiently to permit the switch-operating arm 24 to swing upwardly under bias of the spring 31 to the switch-open position of Fig. 2, thus opening the circuit to the load 41 and the timing motor 16 and terminating operation of both thereof. However, in the event that a plurality of coins x are inserted into the chute 7, but a single coin is received within the notch 20 of the coin carrier during a full revolution thereof. By reference to Fig. 3, it will be seen that the coin x in the chute 7 overlying the coin contained within the notch 20 has its lower portion disposed radially inwardly of the mouth of the notch 20. Rotation of the coin carrier

causes engagement of the overlying coin by the peripheral portion of the coin carrier to move the overlying coin or coins upwardly in the chute 7 against the action of gravity to a point where said overlying coin rests against the periphery of the coin carrier. The longitudinally-arcuate form of the chute 7 prevents an excessive amount of coin weight from bearing directly against the coin carrier 10; and, inasmuch as said coins must be moved upwardly in the chute by rotation of the coin carrier, said reverse movement of the overlying coins is accomplished by rotation of the coin carrier without placing undue strain upon the motor 16 and transmission connecting the motor and the coin carrier. After the first one of a group of coins x has been discharged from the coin carrier 10, continued rotation of the coin carrier will position the notch 20 therein as in Fig. 5, whereby to permit the second coin to move under the action of gravity into contact with the arcuate side portion 21'. As the coin carrier 10 continues to rotate, said second coin x moves into engagement with the inturned end 29 of the switch arm 24 to maintain the switch 22 in a switch-closed position, the coin being moved by said inturned end 29 into the cradle or nest 21. This movement of the coin x into the cradle 21 permits movement thereof past the end of the arm 24 and subsequent engagement of the arm by the coin carrier 10 as above described. Thus, it will be seen that the motor 16 and the load 41 will be maintained in continuous operation until all of the coins deposited in the chute 7 have been discharged therefrom. The time required for one complete revolution of the coin carrier 10 is determined by the speed of rotation of the armature of the motor 16 and the gear ratio therebetween and the shaft 12.

To insure proper discharge of the coins x from our novel timing mechanism, we provide a coin ejector 48 rigidly secured at one end portion to the lower end of the guide plate 4 by a screw or the like 49. The coin ejector 48 is made from resilient material such as spring steel or the like and bifurcated to form a pair of parallel inner and outer legs 50 and 51 respectively extending tangentially in the direction of rotation of the carrier or from the left to the right with respect to Figs. 2 to 5 inclusive. The free ends of the legs 50 and 51 terminate in aligned inner and outer lips 52 and 53 respectively sloping toward the coin carrier 10 and the frame 1 and extending angularly with respect to one side of the notch of the carrier 10 when said carrier is rotated sufficiently to position the arcuate side portion 21 adjacent thereto. As shown, the guide plate 4 is notched at the lower end portion of the recess 8 and at the open side 9 thereof. The lip 52 and leg 50 which overlies the coin carrier 10 adjacent the periphery thereof enters the notch 54 and has frictional engagement with the coin carrier 10, whereas the outer lip 53 engages the rear wall 2 of the frame 1 radially outwardly of the coin carrier. It will be noted that the inner and outer lips 52 and 53 form one wall of a discharge portion or chute 55 extending angularly downwardly from the recess 8. The ejector 48 exerts a yielding bias of the legs 50 and 51 thereof toward the coin carrier 10 and the rear wall 2 of the frame 1. Thus as the coin carrier rotates, the lip 52 will enter the notch 20 and have camming engagement with the coin x whereby the coin is removed entirely from the carrier 10. The coins x will normally drop out

of the notch 20 under the action of gravity without engaging the lips 52 or 53. However, under continued use, there is a possibility that foreign matter may be introduced into the coin chute or that a sticky or gummy coin may be used. The relatively slow movement of the coin carrier gives opportunity for sticky or gummy substances to accumulate at the discharge end of the recess 8 sufficiently to prevent a coin from dropping freely therethrough. When this condition occurs, the coin x is moved by the carrier against the wall-acting lips 52 and 53, whereby the coin is ejected in spite of its tendency to remain in the notch 20 of the carrier. From the above, it should be obvious that our novel timing mechanism may be used for controlling a power-operated load for a predetermined set time interval determined by the number of coins or tokens placed in the coin chute. The channel 7 in the guide plate 4 is provided with a longitudinally-extended sight opening 6' through which the operator may observe the number of coins contained in the chute. By this means, the operator may tell at a glance how many revolutions the coin carrier 10 must make before the switch 22 is opened to disconnect the load circuit.

Our invention has been thoroughly tested and found to be completely satisfactory for the accomplishment of the objectives set forth; and while we have shown and described a preferred embodiment of our novel timing mechanism, it will be understood that the same is capable of modification within the spirit and scope of the invention as defined in the claims.

What we claim is:

1. A coin ejector for a coin-operated timing mechanism including a frame, a coin chute, a rotary coin carrier journalled in said frame and interposed in said coin chute, said carrier having

10
15
20
25

a coin-receiving notch registrable with the coin chute, and mechanism for rotating said coin carrier, said coin ejector comprising a flexible resilient member mounted at one end to said frame, the free end portion of said member being bifurcated to provide longitudinally parallel inner and outer legs extending tangentially in the direction of rotation of said carrier, the free ends of said legs terminating in aligned inturned inner and outer lips respectively sloping toward said carrier and frame and extending angularly with respect to one side of the notch in said carrier when the carrier is rotated sufficiently to position said side adjacent said lips, the inner one of said lips overlying a portion of said coin carrier adjacent the periphery thereof, said outer lip being radially outwardly spaced therefrom, said lips being yieldingly biased toward engagement with said carrier and frame respectively, whereby said inner lip will enter the notch in said carrier upon rotation thereof and have camming engagement with a coin contained in the notch to initiate ejecting movements thereto, said ejecting movement being enhanced by engagement of the coin with said outer lip.

2. The structure defined in claim 1 in which said lips define one side of said coin chute adjacent the discharge end thereof.

ARNOLD R. DAHLBERG.
RAYMOND T. LARSON.
RICHARD M. CHAPMAN.
